(57) CLAIM

I claim, the ornamental design of a coordinate input device,
as shown and described.

DESCRIPTION

FIG. 1 is a top plan view of a coordinate input device
according to the invention, with the broken line showing
indicating a removable component;

FIG. 2 is a bottom plan view thereof;

FIG. 3 is a right side elevational view;

FIG. 4 is a left side elevational view;

FIG. 5 is a rear elevational view;

FIG. 6 is a front elevational view; and,

FIG. 7 is a rear perspective view.
